STEPHEN Q. CAREY, OF WAXAHATCHIE, TEXAS.

Letters Patent No. 83,926, dated November 10, 1868.

IMPROVED HAY AND COTTON-PRESS.

The Schedule referred to in these Letters Patent and making part of the same.

To all whom it may concern:

Be it known that I, STEPHEN Q. CAREY, of Waxahatchie, in the county of Ellis, and State of Texas, have invented a new and improved Hay and Cotton-Press; and I do hereby declare that the following is a full, clear, and exact description of the construction and operation of the same, reference being had to the accompanying drawings, making a part of this specification, in which—

Figure 1 is a vertical section through line xx of fig. 2.

Figure 2 is a rear view, a portion of the wall being removed.

The object of this invention is to provide a press which shall be simple and neat in construction and appearance, which can be conveniently and rapidly worked, and the operation of which shall be such that the platen, in starting, moves quickly, but as it approaches the end of its movement its velocity decreases, and its power proportionately increases.

In the drawings, B is the press-box, supported by a frame, A, and containing the platen P, which compresses the hay or cotton into a bale, at the upper end of the box.

C are doors, hinged to the frame A at $a a$, and provided with a cross-bar, e, attached to their outer side by a headed bolt and slot, b, and having tenons, c c, that, when the doors are closed, enter notches or mortises in the frame-timbers at $d d$, and thereby hold the doors firmly in place during the compressing of the bale.

The top or cover E is strengthened by braces E' E', and is hinged to the top of the frame at $e e$, so that it can be turned back out of the way when filling the press-box with hay or cotton. The under side of the cover E has attached to it a bed, F, with cross-grooves, to receive the bale-hoops.

The platen is raised, to compress the bale, by means of a cord or chain, G G, running in grooves or slots, g g, in the end walls of the box, and passing over pulleys H H', in the cover E, and then down, outside of the press-box, at each end of the box, one end of the cord or chain being fastened to a tapering spirally-grooved pulley, I, on a shaft, J, under the press-box, and the other end being fastened to a similar pulley, I', on the other end of the same shaft.

The cord G is continuous, passing from pulley I over

pulley H, thence down in the groove g, to the end of the platen, and over a pulley in such end, thence to and once around a spool or pulley, M, on the other side of the platen, thence to the other end of the platen, over the pulley there, up groove g, over pulley H, and down to pulley I'.

K is a large pulley at the middle of the shaft J, from which a cord or chain, N, passes to a capstan, L, where the power is applied to the press. By turning the capstan L, the shaft J and pulleys I I' are rotated, raising the platen against the cotton or hay in the upper end of the press-box.

At first, while the hay is but little compressed, its resistance to the platen is but small, and the latter can be moved with considerable speed, with the outlay of but little power.

To accommodate my press to this fact, I have provided the tapering pulleys I I', having the spiral groove i i. The cord G is fastened at the outer end of the grooves i i, and, as the pulleys are turned, winds up in the groove. Accordingly, when the platen is first starting, and till it approaches the end of its upward movement, the cord G, winding around the larger end of the pulleys I I', raises it with great rapidity, but as it nears the upper end of its movement, the cord, having wound down to the small end of the pulleys, moves it much more slowly, but with greatly increased power.

The whole arrangement is very simple. The press is strong and durable, and can be operated with much greater speed and convenience than the screw-presses, and other presses in common use.

I am aware that the several devices herein described, and mainly also their combination, are not new, and I do not therefore claim any of said devices separately, but

The arrangement, herein described, of the shaft J, pulleys I I', cord G, pulleys H H', platen P, press-box B, capstan L, cord or chain N, and large flanged pulley K, all constructed and operating substantially as set forth.

To the above specification of my improvement, I have signed my hand, this 8th day of August, 1868.

S. Q. CAREY.
